TICKET PAD

Milton H. London, Detroit, Mich.

Application August 22, 1950, Serial No. 180,863

4 Claims. (CL 283—53)

1

This application relates to ticket pads and more particularly to pads of tickets such as are used in motion picture theaters. Such pads are generally of rectangular, zig-zag, folded form having one or more, but generally five, tickets to the fold, with the ticket edges forming the face of the pad.

Each ticket is marked on each of the opposite ends of the face side of the ticket with a serial number, and the left end of the ticket, except for such a number, is not identical with the right end. It is the practice to sever each ticket on its center line, either end being retained as a stub for checking purpose. Such severing may be done in a machine which receives the ticket, severs it centrally, retains the leading end of the entered ticket as a stub, and ejects the trailing end.

An object of the present invention is to provide a pattern of marking on the faces of a pad of such tickets of such a nature that when halves or stubs are consecutively stacked and superimposed vertically with their edges aligned, the sides of the stack of stubs thus formed will show a double line or intersecting line pattern. Interruptions of that pattern on the stack will reveal whether or not the interruption of the double line pattern on the stack is due to an interruption of orderly sequence of stacking or due to imperfections in the stubs being stacked.

In a prior Patent No. 2,525,918 of October 17, 1950, I have disclosed a ticket pad having a criss-cross pattern marking on its faces to reveal the order of stacking of stubs of tickets severed from that pad. That pattern may be characterized as a single line pattern because the stubs when stacked will show a single line pattern on the stack. In this application I disclose a double line pattern, named such because, when stubs from a pad thus marked are stacked, a pattern of two intersecting lines will appear on the stack of stubs.

The single line pattern is such that an interruption of the single line pattern of the stack of stubs cannot be interpreted in a manner to discriminate among the two types of factors which cause an interruption of the pattern, whereas, the double line pattern is such that an interruption of the double line pattern of the stack of stubs can be interpreted readily to discriminate between the two types of factors causing interruption of stack pattern.

There are two types of factors which cause interruption of stack pattern. The first type is the interruption of sequence of stacking. The sec-

2

ond type is imperfection of manufacture or of stacking of the stubs. In the second type there are these several factors:

(a) The stacking of the stubs in the stack receiver might not be in truly vertical alignment, with the result that the stack pattern may be interrupted.

(b) The tickets may not be severed accurately in the machine which issues single tickets from a pad of tickets, and it may be that some tickets are longer or shorter than normal, and, in either case, stubs of tickets out of normal length, when stacked, will show an interruption of the stack pattern.

(c) The stubs may not be severed accurately from the tickets and it may be that some stubs are longer or shorter than normal, and these, when stacked, will show an interruption of stack pattern.

20 The single line pattern cannot be interpreted or read to enable the reader to discriminate between the two types of factors above mentioned, but the double line pattern of this application can be interpreted to discriminate between interruptions of stack pattern due to interruptions of sequence, or interruptions of stack pattern due to imperfections of stacking or cutting or shaping of stubs to be stacked.

Now, where a single line pattern is used, an 30 interruption in the single line stack pattern will indicate that the stacking was not in the order in which the tickets were removed from the pad, indicating missing or out-of-order tickets, or will indicate imperfect stacking or severance of stubs.

35 However, if a double line pattern is used, as disclosed in this application, a major interruption in the double line stack pattern may be interpreted readily to indicate either that the stacking was not in the order in which the tickets

40 were removed from the pad or that the stacking was in order but that the stubs were not stacked in perfect vertical alignment or were not severed perfectly. Obviously since the person charged with interpreting stacks of stubs to locate out-of-order stubs is not concerned with interruptions of pattern due to imperfections of severance or stacking but is concerned only with interruptions in the sequence of stacking, he can ignore

45 50 55 interruptions of pattern due to imperfect stacking or severance and can confine his attention at once to out-of-order tickets evidenced by such interruptions of stack pattern as are seen at once to be due to nothing but interruptions of sequence of stacking.

One embodiment of the invention is shown in the appended drawing.

In this drawing:

Fig. 1 is a half scale side view of a pad of tickets showing its exposed face composed of edges of tickets marked with a predetermined geometric pattern.

Figs. 2-5 are half scale views showing folds of five tickets of the pad of Fig. 1, as if on lines 2-2, 3-3, 4-4, 5-5, of Fig. 1, and indicating the marking on their edges.

Fig. 6 is a view showing a fragment of a stack of stubs of Fig. 1 with the double line pattern indicated, with the stubs being shown twice as long as the ticket halves of Figs. 1-5, though of the same relative number per inch of stack height.

A motion picture theater ticket 10 may be severed from a pad of them and then severed on its own center line, as is presently the practice, to form a stub. Stubs may then be stacked. There are four possibilities for stacking stubs. The left end of the ticket may be its leading end as the ticket is inserted in a machine which severs the ticket and uses the leading end to form a stub and to form a stack of stubs and the stub may be stacked with its face up or with its face down. The right end may be the leading or stub end and the stub may be stacked with its face up or with its face down.

A pad 12 of such tickets consists of a large number of tickets joined end to end, with the individual tickets separated by score lines 14.

A conventional pad is formed as shown in Fig. 1 where 2,000 tickets are folded over 400 times in a zig-zag or accordion pleated pattern with 5 tickets to the fold. In one embodiment, shown in half scale in Fig. 1, the tickets are 2" long, 1" wide, and of such thickness and stock that the pad of 2,000 tickets, 400 folds, so folded, is 5" high, as well as being 10" long and 1" wide.

Fig. 6 shows a stack of stubs, each 1" long. 400 tickets, in the example shown, have a thickness of 5", and the 400 stubs are shown full length and half thickness in Fig. 6, but half scale in Fig. 1.

In carrying out my invention, I mark on the faces of such pad, made up of the edges of the tickets which form the pad, a pattern of straight oblique lines 20-21-22-23 drawn across the pad criss-cross fashion and in perfect symmetry. Each ticket includes points of eight lines, four to each edge, arranged symmetrically.

Lines 20 and 21 are those of the single line pattern, but lines 22 and 23, form with lines 20 and 21 the double line pattern.

Where lines intersect, the point of intersection may be viewed as two points of separate lines superimposed on one another, which is, in fact, the case, as where the lines are ruled on a formed pad.

The markings on the tickets are generally similar but differ slightly from fold to fold in order that the double line pattern may be formed when the stubs are stacked. No matter which end of the ticket leads and forms the stub that is stacked, and no matter which way the stubs are disposed in the stack, face up or face down, because of the particular pattern disclosed, the stack of stubs will show a perfect double line pattern, provided the stubs are arranged in the stack in the order in which the tickets are removed from the pad and also provided the stubs are stacked in perfect vertical alignment and are of perfect length.

However, if stubs are placed in the stack in a

seriously interrupted order from which the tickets were severed from the pad, or if the stubs are not perfectly severed or stacked, the pattern will be interrupted.

Fig. 6 exemplifies interruptions of pattern and indicates how the causes of interruption may be analyzed as follows:

Stub A, out of pattern, is so because it is either imperfectly stacked, i. e., not stacked in perfect vertical alignment with its adjacent stubs, or because it or the ticket from which it came is imperfectly severed, being shorter than its adjacent stubs, but not because of any interruption of sequence. This may easily be ascertained from the fact that if stub A is moved slightly to the right, to be stacked perfectly, its markings will fit into the pattern and there will be no interruption.

Similarly, the interruption at stub B may be seen at once to be due not to an interruption of sequence of stacking but to the fact that stub B is either not in vertical alignment with its adjacent stubs or is shorter than its adjacent stubs.

The interruption at stub C, however, can be seen at once to be due to interruption of sequence rather than due to stub C being shorter than its adjacent stubs or being out of vertical alignment with its adjacent stubs, and this may be established from the fact that if stub C is moved left or right its markings will not fit into the pattern and complete the pattern at stub C.

Similarly, stub D may be seen to be out of sequence.

Stub E, on the other hand, may be seen to be in sequence, or obviously not out of sequence, but rather either imperfectly stacked or imperfectly cut to be somewhat shorter than the adjacent stubs, and this is demonstrated from the fact that if stub E were pushed slightly to the left, the pattern would be complete at stub E.

In the examples given, stubs A, B, and E have both markings to the same one side of the pattern, stubs A and B to the left, stub E to the right, whereas stubs C and D each have both markings on opposite or different sides of the pattern. This difference gives the clue for interpretation to the reader who is not interested in stubs imperfectly stacked but only in stubs stacked out of sequence. Such reader can ignore stubs which have both markings to one side of the pattern, and can focus his attention on stubs which have both markings on opposite sides of the pattern, or, phrasing this differently, he can focus on stubs whose both markings are outside the pattern or whose both markings are inside the pattern. This latter is not shown, but imagine stub C moved down not merely two or three places where it will be in sequence and thus fall into pattern, but six or seven places where it will be out of sequence and thus fall out of pattern with both its markings inside the pattern.

The double line pattern enables the reader to classify the out of pattern stubs and ignore one class of out of pattern stubs (having both markings on one side of the pattern) and focus on a different class of out of pattern stubs (having both markings on opposite sides of the pattern), but the single line pattern requires the reader to examine all out of pattern stubs since he is furnished with no visible clue while the stubs are still stacked to enable him to determine into which class a particular out of pattern stub may be classified.

The pad pattern may be described as follows:

First, the tickets are of identical length, folded in zig-zag form to form a strip pad of rectangular form having front and back faces, each bounded by horizontal and vertical sides which are formed by the edges of the tickets.

Secondly, the pad pattern includes two criss-crossing or intersecting sets of parallel oblique lines. One set includes lines 20 and 22, the other lines 21 and 23. The horizontally measured distances between the parallel oblique lines of the first set (20, 22) are equal to one-half the length of a ticket. Likewise, the horizontally measured distances between the parallel oblique lines of the second set (21, 23) are also equal to one-half the length of a ticket.

Third, each of the two halves of each of the two ticket edges is at least twice marked so that each quarter edge is at least twice marked, each half four times, each edge four times, each ticket eight times marked.

Fourth, the corresponding marked points of each ticket half are in alignment across the ticket; i. e., they are the same distance from the center line of the ticket of which that half forms a part. This simply means that the markings on the opposed faces of the pad are identical and in alignment across the pad.

Fifth, the intersecting oblique lines are symmetrically arranged with respect to imaginary vertical and horizontal lines passing through the intersections, and the oblique lines bisect the angles at the intersections.

Finally, there are several tickets to a fold, but all the tickets of a fold are substantially identically marked.

In the 10" x 5" x 1" pad exemplified, the marking lines are at 45° angles from horizontal and vertical, and intersect as illustrated to form squares whose diagonals are 1" long.

It is apparent that if stubs are stacked more or less in the sequence in which the tickets are removed from the pad, a double line pattern will form in the stack. The degree of sharpness or fuzziness of the formed pattern reflects how closely the stubs were stacked with reference to their sequence. If the stubs are stacked absolutely consecutively, the pattern will be clear and sharp, except for imperfections due to imperfect stacking out of vertical alignment or imperfect severing resulting in some stubs being shorter than others. Otherwise, the pattern will be sharp. On the other hand, if the stubs are stacked without reference to their natural sequence, the pattern will disappear or at least be interrupted to show interruptions of sequence.

Now having described the ticket pad and pattern here disclosed, reference should be had to the claims which follow for a determination of the invention hereof.

I claim:

1. A patterned ticket pad comprising a continuous strip of end to end connected identical length tickets folded in zig-zag form and thus forming a strip pad of rectangular form having front and back faces each bounded by horizontal and vertical sides and formed by the edges of the tickets, said faces having on each a marking in the form of a predetermined geometric pattern, including two criss-crossing or intersecting sets of parallel oblique lines, with the horizontally measured distances between the parallel oblique lines of the first set being equal to one-half the length of a ticket, and with the horizontally measured distances between the parallel oblique lines of the second set also being equal to one-

half the length of a ticket, each of the two halves of each of the two ticket edges being at least twice marked, the corresponding marked points of each ticket half being aligned, i. e., the same distance from the center line of the ticket of which that half forms a part, the intersecting oblique lines being symmetrically arranged with respect to imaginary vertical and horizontal lines passing through such intersections, with such lines bisecting the angles at such intersections.

2. A patterned ticket pad comprising a continuous strip of end to end connected identical length tickets folded in zig-zag form and thus forming a strip pad of rectangular form having front and back faces, each face being bounded by horizontal and vertical sides, these two faces being formed by the edges of the tickets, each face having a marking in the form of a predetermined geometric pattern, including two criss-crossing or intersecting sets of parallel oblique lines, with the horizontally measured distances between the parallel oblique lines of the first set being equal to one-half the length of a ticket, and with the horizontally measured distances between the parallel oblique lines of the second set also being equal to one-half the length of a ticket, each of the two halves of each of the two ticket edges being at least twice marked, the corresponding marked points of each ticket half being aligned, i. e., the same distance from the center line of the ticket of which that half forms a part, the intersecting oblique lines being symmetrically arranged with respect to imaginary vertical and horizontal lines passing through such intersections, with such lines bisecting the angles at such intersections, there being several tickets to each fold, with all the tickets of a fold being substantially identically marked.

3. A patterned ticket pad comprising a continuous strip of end to end connected identical length tickets folded in zig-zag form and thus forming a strip pad of rectangular form having front and back faces each bounded by horizontal and vertical sides and formed by the edges of the tickets, said faces having on each a marking in the form of a predetermined geometric pattern, including two criss-crossing or intersecting sets of parallel oblique lines, with the horizontally measured distances between the parallel oblique lines of the first set being equal to one-half the length of a ticket, and with the horizontally measured distances between the parallel oblique lines of the second set also being equal to one-half the length of a ticket, each of the two halves of each of the two ticket edges being at least twice marked, the corresponding marked points of each ticket half being aligned, i. e., the same distance from the center line of the ticket of which that half forms a part, the intersecting oblique lines being symmetrically arranged with respect to imaginary vertical and horizontal lines passing through such intersections, with such lines bisecting the angles at such intersections, the patterns being in the form of lines ruled on a formed pad.

4. A patterned ticket pad comprising a continuous strip of end to end connected identical length tickets folded in a zig-zag form and thus forming a strip pad of rectangular form having front and back faces each bounded by horizontal and vertical sides and formed by the edges of the tickets, said faces having on each a marking in the form of a predetermined geometric pattern, including two criss-crossing or intersecting sets of parallel oblique lines, with the horizontally measured distances between the parallel oblique lines of the

first set being equal to one-half the length of a ticket, and with the horizontally measured distances between the parallel oblique lines of the second set also being equal to one-half the length of a ticket, each of the two halves of each of the two ticket edges being at least twice marked, the corresponding marked points of each ticket half being aligned, i. e., the same distance from the center line of the ticket of which that half forms a part, the intersecting oblique lines being symmetrically arranged with respect to imaginary vertical and horizontal lines passing through such intersections, with such lines bisecting the angles at such intersections, there being several

10 tickets to each fold, with all the tickets of a fold being substantially identically marked, the patterns being in the form of lines ruled on a formed pad.
